UNITED STATES PATENT OFFICE.

THOMAS KELLY, OF ELMVALE, ONTARIO, CANADA.

CORK-EXTRACTOR.

SPECIFICATION forming part of Letters Patent No. 402,742, dated May 7, 1889.

Application filed May 21, 1888. Serial No. 274,525. (No model.)

To all whom it may concern:

Be it known that I, THOMAS KELLY, of the village of Elmvale, in the county of Simcoe, in the Province of Ontario, Canada, have 5 invented a certain new and Improved Cork-Extractor, of which the following is a specification.

The object of the invention is to design a simply-constructed, effective-operating, and 10 durable cork-extractor; and it consists in the peculiar combinations and the construction, arrangement, and adaptation of parts, all as more fully hereinafter described and claimed.

Figure 1 is a perspective view of my improved cork-extractor in operation. Fig. 2 is a sectional view of same, showing the parts in the position in which they will appear while in the act of extracting a cork. Fig. 3 is an enlarged detail view of the trip mechanism 15 by which the rotating movement of the corkscrew is altered into the vertical movement necessary for extracting a cork.

In the drawings, A represents a bracket arranged to be clamped to the table B, as shown 20 in Fig. 1; or it may be held in position permanently, if desired.

C is a hollow cylindrical portion of the bracket A, and has formed on it the bearings D to support the pivoted toothed quadrant E, 25 which quadrant has a handle, F, fixed to its spindle, as shown.

G is a hollow sleeve fitted into the cylindrical portion C of the bracket A. A rack, a, is made on one side of the sleeve G and engages with the notched quadrant E, as indicated. 30

H is a plate fixed to the sleeve G, and has a double hole, b, made through it in the shape of the figure 8, as indicated in Fig. 3. The 35 twisted wire I passes through the hole b and is suspended from the top of the cap J, as shown.

K is a plate suspended from the cap J and extending down on either side of the twisted 40 wire I, forming a guide for the said wire.

L is a corkscrew connected to or forming 45 part of the wire I. The cap J is held to the top of the cylinder by a sliding plate, M, fitting in a horizontal slot made in the cap J 50 and designed to engage with the heads of the bolts N, which are secured to the cylinder C,

as indicated in Fig. 3. The spring O holds the plate M below the heads of the bolts N, thereby locking the cap to the cylinder C until the plate M is pushed in sufficiently to 55 clear the heads of the bolts N, when the cap may be raised.

Having now described the parts forming my improved cork-extractor, a few words will suffice to explain its operation.

The point of the corkscrew L is placed in the center of the cork, as usual. The handle F is seized, as indicated in Fig. 1, and is pulled in the direction indicated by the arrow, which motion causes the sleeve G to move upwardly, 60 and as the plate H, with its figure-8-shaped hole b, must move with the sleeve G the twisted wire I is caused to revolve, and the corkscrew is thus made to enter the cork, as indicated in Fig. 2. By the time that the cork 65 has been penetrated sufficiently the handle F has come in contact with the projecting portion of the plate M, forcing the said plate M in until the heads of the bolts N are clear, by which time the top of the sleeve G has 70 struck the cap J, forcing the said cap up, as indicated in Fig. 2, and with it the corkscrew, and in this manner the cork is easily extracted.

What I claim as my invention is— 80

1. The combination, with the bracket having hollow cylindrical portion and ears forming bearings D, of the sleeve working in said cylindrical portion and formed with rack a, the toothed quadrant pivoted in said bearings 85 and engaging said rack, the plate fixed to said sleeve, and the twisted wire passed through said plate and having its upper end secured to a cap resting on said sleeve and extended over the top of said cylindrical portion, substantially as described.

2. The combination, with the bracket having hollow cylindrical portion and ears forming bearings D, of the sleeve working in said cylindrical portion and formed with rack a, 90 the toothed quadrant pivoted in said bearings and engaging said rack, the plate fixed to said sleeve, and the twisted wire passed through said plate and having its upper end secured to a cap resting on said sleeve, the cap J, extended over the top of said cylindrical portion, and the plate K, suspended from said 100

cap within the sleeve and upon each side of the wire, substantially as described.

3. A cylinder, C, sleeve G, a cap, J, resting thereon and extended over the top of said cylinder, the twisted wire or wires I, the corkscrew L, connected to and forming part of the twisted wire or wires I, the upper end of which is pivotally connected to the cap J, and a plate, H, fixed to the sleeve G and having a hole, b, made to fit the twisted wire I, in combination with the toothed quadrant E, provided with a handle, F, and arranged to engage with a

rack formed on the sleeve G, a plate, M, fitted into a horizontal slot made in the cap J and designed to be held below the heads of the bolts N by the spring O and to be pushed out of contact with the said bolts by the passing of the handle F, substantially as and for the purpose specified. 15

Barrie, May 9, 1888.
In presence of—
C. E. HEWSON,
A. E. H. CUESWIEKE.
